UNITED STATES PATENT OFFICE.

CHARLES LEA, OF BOSTON, MASSACHUSETTS, ASSIGNOR TO EVERREADY MFG. COMPANY OF BOSTON.

STAPLING-MACHINE.

1,356,927.

Specification of Letters Patent.

Patented Oct. 26, 1920.

Application filed December 7, 1916. Serial No. 135,525.

To all whom it may concern:

Be it known that I, CHARLES LEA, a citizen of the United States, and a resident of Boston, district of Dorchester, county of 5 Suffolk, State of Massachusetts, have invented an Improvement in Stapling-Machines, of which the following description, in connection with the accompanying drawings, is a specification, like characters on 10 the drawings representing like parts.

This invention relates to stapling machines, being more particularly concerned with a machine for forming staples from a wire and driving them into the work, the 15 machine being especially useful in offices for the fastening together of two or more sheets of paper, although it is susceptible of general use wherever staples are required to fasten thicknesses of material together.

20 My invention will be best understood by reference to the following description when taken in connection with the accompanying drawings of one illustrative embodiment thereof, while its scope will be more particularly pointed out in the appended 25 claims.

In the drawings:

Figure 1 is a front elevation of a staple forming and setting machine embodying my 30 invention;

Fig. 2 is a plan section on irregular line 2—2 in Fig. 1;

Fig. 3 is a side elevation of the machine;

Fig. 4 is a central, longitudinal section of 35 the machine with a portion of the hand lever broken away;

Figs. 5, 6, 7 and 8 are sectional views on line 5—5 of Fig. 3 illustrating the mechanism in various positions, Fig. 5 showing the 40 initial or normal position, Fig. 6 showing the position which the parts occupy just after the wire has been severed, Fig. 7 showing the parts as they appear just after the staple has been formed, and Fig. 8 showing the 45 parts as they appear after the staple has been set.

Fig. 9 is a detailed plan of the gage for the work; and

Fig. 10 is a rear elevation of the machine. 50 Referring to the drawings and to the embodiment of my invention which I have selected for illustration, I have there shown a staple-forming and setting machine having as the preferred staple-forming material a wire 11, supplied in the form of a

coil wound on a suitable spool 12, the latter being herein formed of sheet metal, and provided with two flanges 13 and 14, between which the coils of wire are wound. This spool may be mounted upon a suitable 60 spool holder 15, the latter being herein in the shape of a hub formed as a part of a frame 16, constituting a combined support and housing for the mechanism. In the present instance, the frame is provided with an annular shell or casing 17 which encircles the spool, and there is thus provided between said casing and the hub an annular spool chamber 18 in which the spool is housed. The entrance to the spool chamber is closed 70 by a part of the spool, which is herein the flange 14. The spool may be held in its place in the chamber by any suitable means, herein a retaining spring 19 mounted on a pivot 20 on the hub 15, and adapted to be swung 75 about its pivot across the face of the flange, as illustrated in Figs. 2 and 10, thereby to hold the spool in place. By simply swinging this spool retainer around until it clears the inner circumferential edge of the flange 80 14, the spool may be withdrawn in a rearward direction.

The wire 11 is led from the spool through a suitable opening 21 in the casing 17, whence it is fed by any suitable mechanism, 85 such as that which I will now describe. Mounted on the front face of the combined frame and housing 16 is an oscillating feed member 22, herein provided with a plurality of segmental slots 23, 24 and 25. Suitable 90 guides, herein a plurality of screws or studs 26, 27 and 28 passing through the slots 23, 24 and 25, respectively, are threaded into the front face of the frame and serve to enforce a circular movement of the feed member 22 95 as well as to limit the movement of the latter in opposite directions. The feed member is herein provided with an arm 29 having an opening 30 through which the wire 11 loosely passes. Attached to this arm is a 100 species of feed pawl 31, herein in the form of a spring, secured at 32 to the feed member and having a free end 33 which engages the wire. Also engaging the wire and preferably adjacent the feed pawl is a species of 105 stop pawl 34, herein in the form of a flat spring secured at 35 to the casing 17 and having a free end 36 engaging the wire 11. The stop pawl 34 prevents retrograde movement of the wire during the backward or 110

non-working stroke of the pawl 31 (con-
traclockwise as viewed in Figs. 1 and 5 to 8,
inclusive). When the feed pawl is moved
in the opposite direction it exerts a wedging
action against the wire, firmly clamping
the latter in the hole 30 in the arm 29, there-
by causing the wire to be advanced, it being
understood that at such time the stop pawl
34 tends to swing away from the wire and
10 allow the latter to be advanced without un-
due restraint.

Herein the feed member 22 is moved
on its working stroke by a suitable spring
37 having one end fixed at 38 and its other
15 end bearing against an abutment 39 on
the feed member 22, thereby constantly tend-
ing to move the latter in a clockwise di-
rection (Figs. 1 and 5 to 8, inclusive). The
idle or nonworking stroke of the feed mem-
ber may be produced by any suitable means,
herein the pin 40, which is intermittently
20 brought into engagement with the abutment
39 during the operation of the machine by
suitable means hereinafter described.

25 Turning now to the staple forming and
setting mechanism, the latter herein com-
prises a pair of staple-forming plungers 41
and 42 between which a staple driving
plunger 43 is disposed. These plungers are
30 herein mounted to slide in a suitable guide-
way formed by two side guides 44 and 45, a
rear guide 96 and a front guide 97, the
latter being in the form of a removable
35 plate held between shoulders 98 and 99 of
the side guides and secured to the latter
by screws 100.

Coöperating with the staple forming
plungers 41 and 42 is a staple-forming
block 103 across which the wire 11 is fed
40 by the wire feeding mechanism hereinbe-
fore described. The free end of the wire
is guided into its place across the forming
block by a wire guide, the latter herein for
convenience of manufacture being formed
45 as a part of the side plunger guide 44, by
simply providing the latter with a perfora-
tion 105 slightly larger in diameter than the
wire. This guide, moreover, as will pres-
ently appear, constitutes a cutter which, in
50 coöperation with the forming plunger 41
during the early part of the descent of the
latter serves to sever the wire. Prepara-
tory to this cutting of the wire, its advanc-
ing end is brought against the inner face
55 of the side plunger guide 45, which stops
the wire and serves as a gage for determin-
ing the length of wire which is to be cut
off preparatory to the formation of the
staple.

60 The plungers may be actuated in properly
timed relation by any suitable means. In
the present instance, cams 46 and 47, co-
operating with the plungers 41 and 42, re-
spectively, cause the latter to descend in
65 unison and somewhat in advance of the

plunger 43, the latter being actuated by a
cam 48. This cam, for convenience of manu-
facture, is herein formed as a part of an
actuating lever 49, provided with a suitable
70 handle 50, which may be struck or pressed
upon by the palm of the hand in a down-
ward direction to cause the cams to operate
their respective plungers. As a means for
limiting the movement of this lever, the
75 latter is herein provided with two arms or
lugs 51 and 52 arranged to strike suitable
stops. In the present example, the plate
97 serves as a convenient stop for the arm
51 to limit the downward motion of the
80 lever, while the upward motion of the latter
is limited by the arm 52 striking against
a stop 53, herein formed as a part of the
hub 15. A suitable spring 54 serves to re-
store the plungers and the actuating lever
85 to their initial positions after having been
depressed. Herein, this spring is of gener-
ally U-shaped form, and extends across and
beneath lugs 55 and 56 formed on the
plungers 41 and 42, respectively, and a lug
57 formed on the plunger 43. The arms of
90 the spring are preferably provided with
coils 58, while the terminal portions 59 of
said arms are secured to a suitable support
60 herein a part of the hub 15, the latter
being herein drilled as at 61 to provide
95 sockets for the ends of the spring. The
cams 46, 47 and 48 are herein secured to-
gether and mounted upon a shaft 62, which
constitutes a fulcrum for the actuating
lever 49.

100 The staple forming block, hereinbefore
referred to, it will be observed, is disposed
intermediate the paths of the forming
plungers and in the path of the driving
plunger, and since it is in the path of the
105 latter, suitable provision must be made to
cause said forming block to recede from
the path of said driving plunger during
the working stroke of the latter. This may be
accomplished by any suitable means, but
110 herein the forming block is provided with
means for utilizing the working stroke of
the driving plunger to cause said forming
block to recede from the path of said plun-
ger. In the present instance, the forming
115 block is mounted to slide in a suitable guide-
way 63 formed in the combined frame and
housing 16. This guideway is transverse
to the path of the driving plunger 43 and
permits the forming block to recede in a
120 rearward direction against the tension of
a suitable spring 64. Herein the forming
block is provided with an appropriately
formed cam 65 having a face which is
oblique with respect to the path of the driv-
ing plunger 43, so that as the latter de-
scends and its lower end engages such
oblique surface, the forming block is forced
in a rearward direction and caused to re-
cede from the path of the driving plunger. 130

The latter can then continue its descent to drive the staple in the manner hereinafter described.

Referring now to the forming plungers 41 and 42, the inner or opposed faces of the latter are herein provided respectively with grooves 66 and 67 disposed lengthwise thereof and of such proportions in cross section as to receive the wire. As before stated, the latter is fed across the forming block (see Fig. 5); it is then severed (see Fig. 6), and further descent of the forming plungers 41 and 42 causes the projecting ends of the previously cut piece of wire to be bent in a downward direction (see Fig. 7), it being understood, of course, that the intermediate portion of the wire rests upon the forming block 103 and thus enforces the formation of a U-shaped staple. The grooves 66 and 67 receive the legs of this staple as they are formed, and when, upon descent of the driving plunger 43, the forming block 103 is caused to recede from the path of the driving plunger, the staple is then supported in the grooves of the forming plungers by reason of the frictional engagement of the staple legs with the grooves, it being understood, of course, that the staple legs will have a sufficient tendency to spring in an outward direction to cause the staple thus to be held in readiness for the action of the driving plunger. The latter now continues its descent, while the forming plungers 41 and 42 remain stationary, and thus the staple is forced in a downward direction and its legs compelled to pass through the work.

As a means of clenching the staple legs, I prefer to employ the anvil 68 provided with a depression 69 having appropriately formed grooves 70 to receive the staple legs and bend them inwardly (see Fig. 8). By this means the staple is set or clenched and the thicknesses of material 71 through which it is driven are united.

The anvil 68 is herein mounted on a suitable base 72, the latter being herein for convenience of manufacture formed of thin sheet material pressed into the desired shape and preferably provided with suitable legs, herein rubber cushions or pads 73, one at each corner of the base. These cushions are intended to rest upon the desk, table or other support and prevent the latter from becoming scratched. The anvil may be secured to the base in any suitable manner, but is herein combined with a work gage 74, the latter being provided with abutments 75 for the edge of the work and a slot 76, which latter receives a plate 77 interposed between the bottom of the anvil and the top of the base. This plate fills the slot 76 from side to side and serves as a guide for the gage. A clamping screw 78 introduced in an upward direction through the base 72 and plate 77 is threaded into the anvil and serves the dou-

ble purpose of clamping the anvil in fixed position on the base and causing the anvil to clamp the gage 74 to its base. By simply loosening this screw very slightly the gage may be moved forward or backward within the range of its adjustment, thus to determine the distance between the edge of the work and the staples which are to be driven therein, after which the screw is tightened, thus securely holding the gage in the selected position of adjustment.

The frame 16 may, and herein does, constitute a convenient species of presser to hold the work firmly upon the anvil while the staple is being driven, and to this end said frame is pivoted on the base, the latter for this purpose being provided with a depression 79 in which is disposed a boss 80 secured therein by a screw 81. This boss is herein provided with a hole 82 through which a shaft or pin 83 passes into a pair of ears 84 formed on the frame 16. The latter is herein provided with yielding means tending to maintain the same normally in an elevated position, thus to hold the staple forming and driving mechanism and the presser foot elevated above the anvil to permit of the introduction of the work therebetween. To this end I have herein provided a spring 85 of generally U-shaped form, similar to that hereinbefore described, and having coiled portions 86 and arms 87, the latter being inserted in holes 88 provided therefor in the boss 80. This spring exerts a constant tendency to urge the frame 16 in an upward direction away from the anvil, but is of sufficiently light tension to permit the frame at once to descend upon the work the moment downward pressure is applied upon the handle 50.

The combined frame and housing 16 as herein constructed constitute a convenient support for a staple-forming and driving mechanism as well as for the wire feeding mechanism, both of these mechanisms being herein organized so that the former is partially disposed within the latter, thus producing a very neat, compact and efficient organization. This result is herein obtained by making the hub 15 hollow to receive some of the working parts of the staple-forming and driving mechanism. From an inspection of Figs. 2, 4 and 10 it will be observed that the hub 15 has an opening 89 in which the cams 46, 47 and 48 are disposed, the latter being herein held against axial movement by a pair of washers 90 and 91. The shaft or pin 62 which constitutes the fulcrum for the cams and the actuating lever 49 is mounted in the hub 15, the latter for such purpose being provided with holes 92 and 93 which receive the terminal portions of the shaft. In order to permit the introduction and withdrawal of the latter, the casing or shell 17 is provided with perfora-

tions 94 and 95. It will be understood, of course, that when the shaft is to be introduced or withdrawn, the wire holding spool must first be removed from its chamber.

- 5 The pin 40 hereinbefore referred to in connection with the description of the wire feeding mechanism may be conveniently mounted upon the lever 49 to partake of the latter's upward and downward movements.
- 10 When the lever is depressed during the first part of its movement, the pin 40 travels idly and finally brings up against the abutment 39, whereupon the latter is depressed against the tension of the spring 37 and by this means the feed member 22 is given its idle or non-working stroke during the formation and driving of a staple. The working stroke of the feed member, as before stated, takes place under the influence of
- 20 the spring 37 and this occurs during the restoration of the staple-forming and driving mechanism to its initial position. It is therefore evident that with each working stroke of the lever 49 a staple is completely formed and driven.

While I have herein shown and described one form or embodiment of my invention for illustrative purposes and have disclosed and discussed in detail the construction and arrangement incidental to one specific application thereof, it is to be understood that the invention is limited neither to the mere details or relative arrangement of parts, nor to its specific embodiment herein shown, but that extensive deviations from the illustrated form or embodiment of the invention may be made without departing from the principles thereof.

Having thus described one embodiment 40 of my invention what I claim and desire by Letters Patent to secure is:

1. In a stapling machine, the combination of staple-forming means, and means for feeding staple-forming wire thereto, the last-mentioned means including a wire-holding spool inclosing a portion of the first-mentioned means.
2. In a stapling machine, the combination of staple-forming means, and means for feeding staple-forming wire thereto, the last-mentioned means including a wire-holding spool and a wire-progressing device inclosing a portion of the first mentioned means.
3. In a stapling machine, the combination of staple-forming means, means for feeding staple-forming wire thereto, including a spool, and a hollow hub upon the outside of which said spool is mounted and within which hub a portion of said staple-forming means is disposed.
4. In a stapling machine, the combination of staple-forming means, means including a spool for supplying staple-forming wire thereto, and common supporting means

therefor including a hollow hub upon the outside of which said spool is mounted and within which hub a portion of said staple-forming means is disposed.

5. In a stapling machine, the combination of staple-forming means including a rocking member and a reciprocating member actuated thereby, means including a spool for supplying staple-forming wire to said staple-forming means, and common supporting means therefor including a hollow support upon which said spool is mounted and within which said rocking member is disposed, and a support on which said reciprocating member is mounted for co-operation with said rocking member.

6. In a stapling machine, the combination of staple-forming means including a rocking member and a reciprocating member actuated thereby, means including a spool for supplying staple-forming wire to said staple-forming means, and common supporting means therefor including a hollow hub about which said spool is mounted to turn, within which hub said rocking member is disposed and on one end of which hub said reciprocating member is mounted.

7. In a stapling machine the combination of staple-forming means including a rocking member and a reciprocating member actuated thereby, means including a spool for supplying staple-forming wire to said staple-forming means, and a combined support and housing therefor comprising a hub about which said spool is mounted to turn, a pivotal support for said rocking member, a guide for said reciprocating member, and an inclosure for said spool.

8. In a stapling machine, the combination of staple-forming means including a rocking member and a reciprocating member actuated thereby, means including a spool for supplying staple-forming wire to said staple-forming means, and a combined support and housing therefor having an annular chamber in which said spool is disposed, an inner chamber in which said rocking member is disposed, and a guideway in which said reciprocating member is disposed.

9. In a stapling machine, the combination of staple-forming means including a rocking member and a reciprocating member actuated thereby, means including a spool for supplying staple-forming wire to said staple-forming means, and a combined support and housing therefor having an annular chamber in which said spool is disposed, a part of said spool constituting a closure for the entrance to said chamber, an interior chamber in which said rocking member is disposed, and a guideway in which said reciprocating member is disposed.

10. In a fastener setting machine, the combination of fastener setting instrumentalities including an anvil; gaging means

for positioning the work with relation to said anvil, a base on which said anvil is mounted, and means to secure said anvil to said base and to coöperate with said anvil 5 to secure said gaging means in proper relation thereto.

11. In a fastener setting machine, the combination of fastener setting instrumentalities including an anvil; gaging means for 10 positioning the work with relation to said anvil; a base on which said anvil is mounted, and means extending through said base to secure said anvil to said base and to coöperate with said anvil to secure said gaging 15 means in proper relation thereto.

12. In a fastener setting machine, the combination of fastener setting instrumentalities including an anvil; gaging means for 20 positioning the work with relation to said anvil; a base on which said anvil is mounted, and means extending through said base and having screw-threaded engagement with said anvil to secure said anvil to said base and to coöperate with said anvil to secure 25 said gaging means in proper relation thereto.

13. In a fastener setting machine, the combination of fastener setting instrumentalities including an anvil; gaging means for 30 positioning the work with relation to said anvil; a base on which said anvil and said gaging means are supported; means on said base to guide and position said gaging means and to permit adjustment of the latter with reference to said anvil; and means to secure 35 said anvil to said base and to coöperate with said anvil to secure said gaging means in the desired position of adjustment.

14. In a fastener setting machine, the combination of fastener setting instrumentalities including an anvil; gaging means 40 for positioning the work with relation to said anvil, said gaging means being provided with a slot; a base on which said anvil and said gaging means are supported; 45 means located in said slot to guide said gaging means and to permit adjustment of the latter with relation to said anvil; and means extending through said slot to secure said anvil to said base and to coöperate with 50 said anvil to secure said gaging means in the desired position of adjustment.

15. In a fastener setting machine, the combination of fastener setting instrumentalities including an anvil; gaging means 55 for positioning the work with relation to said anvil, said gaging means being provided with a slot; a base on which said anvil and said gaging means are supported; an oblong member located in said slot to 60 guide said gaging means and to permit adjustment of the latter with reference to said anvil, said member being provided with a perforation; and a member extending through said perforation and having thread- 65 ed engagement with said anvil to secure

said anvil and said gaging means to said base.

16. In a stapling machine, an annular member having provision for supporting a wire coil thereabout, a staple former and 70 means to feed wire from the coil to the former comprising an arc-shaped oscillating element mounted on said annular member.

17. In a stapling machine, an annular member having provision for supporting a 75 wire coil thereabout, a staple former and means to feed wire from the coil to the former comprising an arc-shaped element mounted on said annular member for oscillation on the same and having provision for 80 gripping the wire on one phase of its oscillation.

18. In a stapling machine, an annular member having provision for supporting a wire coil, a staple former, an arc-shaped 85 feed member mounted to oscillate on a face of said annular member and having provision for gripping the wire on one phase of its oscillation and means for operating the feed member by the movement of the staple 90 former.

19. In a stapling machine, an annulus having provision for supporting a wire coil thereabout, staple forming plungers extending substantially radially from said annulus, rocking operating devices for said plungers within the annulus and a device for 95 feeding wire from the coil to the plungers mounted on the face of the annulus.

20. In a stapling machine, an annulus having provision for supporting a wire coil thereabout, staple forming plungers extending substantially radially from said annulus, rocking operating devices for said plungers within the annulus and a device for 100 feeding wire from the coil to the plungers comprising an arc-shaped member mounted on the face of the annulus and having an oscillatory movement of partial revolution.

21. In a stapling machine, an open-centered frame, staple forming plungers carried thereby, means for operating the plungers located in the center of said frame and wire feed means comprising an oscillating member on the face of said frame having wire 115 gripping means associated therewith and operable in correlation with said plungers.

22. In a stapling machine, an open-centered frame, staple forming plungers carried thereby, means for operating the plungers located in the center of said frame and wire feed means comprising a member having pin and slot connection with said frame and having wire gripping means associated therewith and means correlating with movement of the plungers for oscillating the member.

23. In a stapling machine, an annular frame, staple forming plungers extending radially thereof, driving means therefor 130

located within the opening of the annulus, an arc-shaped member having pin and slot connection with the face of the annulus, wire gripping means associated therewith 5 and means to oscillate the member in correlation with the movement of the plungers.

24. In a stapling machine, a frame, an arc-shaped member mounted for partial rotation thereon and having wire gripping 10 means, a spring for thrusting said member to one limit of its movement, staple forming plungers extending transversely of the frame, means for reciprocating them and means to move the member against the 15 spring on one phase of the reciprocation.

25. In a stapling machine, a base, an arm pivoted thereon, a transverse enlargement of said arm having provision for holding a wire coil thereabout, staple forming plungers extending transversely of the enlargement, means on the enlargement to feed wire 20 to the plungers and an anvil on the base coöperating with the plungers.

26. In a stapling machine, a base, an arm pivoted thereon, an annulus transverse to 25 the arm having provision for holding a wire coil thereabout, rockable plunger-operating devices in the opening of the annulus, staple

forming plungers carried radially of the annulus, means on the annulus for feeding 30 wire to the plungers and an anvil on the base coöperating with the plungers.

27. In a stapling machine, an annular or open-centered frame, staple forming and driving plungers carried thereby, a lever for 35 operating the plungers pivoted at the center of the frame, and stops carried thereby adapted to engage the frame at opposite sides thereof to limit oscillatory movement of the lever.

28. In a stapling machine an open-centered frame having a transverse shaft journaled therein, a set of staple forming and driving plungers arranged longitudinally of the shaft, cams on the shaft for operating 45 the plungers and an operating lever for operating the shaft projecting transversely from the center of the frame.

29. A machine as described in claim 28 wherein the frame provides for the support 50 of a coil of staple-forming wire concentrically thereabout.

In testimony whereof, I have signed my name to this specification.

CHARLES LEA
